United States Patent Office

Des. 176,503
Patented Jan. 3, 1956

176,503

LIFT TRUCK

Robert C. Brown, Portland, Oreg., assignor to Hyster
Company, Portland, Oreg., a corporation of Oregon

Application July 27, 1953, Serial No. 26,136

Term of patent 14 years

(Cl. D14—3)

FIG. 2

Fig. 1 is a view in perspective, taken from the front right of the lift truck, showing my new design; and

Fig. 2 is a view in perspective, taken from the rear left of the lift truck.

I claim:

The ornamental design for a lift truck, as shown.
